GRAPHIC RECORDER HOUSING

Edward E. Austin and Richard M. Kemplin, Los Angeles,
Calif., assignors to F. L. Moseley Co., a corporation of
California

Application August 9, 1956, Serial No. 42,554

Term of patent 14 years

(Cl. D26—14)

Fig. 1 is a front elevational view of a graphic recorder housing showing our new design; and

Fig. 2 is a side elevational view thereof.

The dominant features of our new design are shown in solid lines in the drawing.

The broken line fragmentary shown of a representative cabinet to which the housing may be attached is for illustrative purposes only.

We claim:

The ornamental design for a graphic recorder housing, as shown and described.
